Wilbur M. Day, Kenwood, Ohio, assignors to
The Baldwin Company, Cincinnati, Ohio, a corporation of Ohio

Application May 22, 1952, Serial No. 19,834

Term of patent 14 years

(Cl. D56—9)

To all whom it may concern:

Be it known that we, William Millington and Wilbur M. Day, citizens of the United States of America, residing at Grand Rapids, in the county of Kent and State of Michigan, and at Kenwood, in the county of Hamilton and State of Ohio, respectively, have invented a new, original, and ornamental Design for a Piano Case, of which the following is a specification, reference being had to the accompanying drawing forming a part hereof.

The figure is a perspective view of a piano case, showing our new design.

We claim:

The ornamental design for a piano case, substantially as shown.

WILLIAM MILLINGTON.
WILBUR M. DAY.
